UNITED STATES PATENT OFFICE

HERMAN WEGNER, OF GROTON, SOUTH DAKOTA.

COMBINED DRILL, REAMER, AND PIPE-PULLER.

SPECIFICATION forming part of Letters Patent No. 465,103, dated December 15, 1891.

Application filed June 10, 1891. Serial No. 395,759. (No model.)

To all whom it may concern:

Be it known that I, HERMAN WEGNER, a citizen of the United States, residing at Groton, in the county of Brown and State of South Dakota, have invented certain new and useful Improvements in a Combined Drill, Reamer, and Pipe-Puller; and I do hereby declare the following to be a full, clear, and exact description of the invention, such as will enable others skilled in the art to which it appertains to make and use the same.

My invention relates to drilling and reaming tools of the character specially designed for use in sinking bored-well casings or tubes.

The object of the invention is to provide a drill and reamer which shall be simple in construction and durable and efficient in use, and by means of which tube and case drilling operations may be conveniently performed and the tubes or casings withdrawn at pleasure without the necessity of employing separate tools for accomplishing such results.

To this end my invention consists, essentially, in a combination-tool which is adapted to be readily converted either into a drill and reamer or a tube puller or lifter, according to requirements.

My invention also consists in certain improved features of construction and combination of parts, all as hereinafter described, and particularly pointed out in the claims at the end of this description.

Referring to the accompanying drawings, which form a part of the specification, Figure 1 represents a sectional elevation of the combined drill and reamer, showing the expandable jaws in operative positions below the casing or tube section. Fig. 2 is a similar view showing the jaws confined within the casing in a contracted position. Fig. 3 is a sectional elevation of the bit or cutting-section of the drill proper detached from the drill-head. Fig. 4 is a sectional elevation of the device arranged for use as a tube puller or lifter. Fig. 5 is a detail illustrating the pipe-puller.

Like letters of reference are used to designate like parts in each of the several views.

A designates the drill-head, to which the expandible cutting-jaws and sliding bit are removably secured, as hereinafter set forth.

A' is the bit or cutting section of the drill proper, which is preferably constructed with a cutting-edge *a* and an enlarged head *a'*, 55 formed integrally with an arrow-headed shank B B', which is fitted to slide vertically in a socket C, formed in the lower end of the drill-head A, the movements of the bit being limited by the shoulders *b* of the arrow-head B' 60 and the enlarged head *a'* of the bit which come in contact with the top and bottom edges, respectively, of the wall surrounding the socket C. The shank B is provided with an elongated recess or slot *b'*, which preferably extends transversely through the shank and has seated therein a coiled or other suitably-shaped spring or springs D, which rest upon a follower *b*² and bear against the upper wall of said recess, so as to exert a constant 70 pressure, tending to lift the bit A', and thus hold the same normally in an elevated position with its head *a'* resting against the lower end of the drill-head.

E E designate expanding jaws or reamers, 75 which are held normally in an expanded position or with their lower ends thrown outward, as shown in Fig. 1, by means of the arrow-headed portion of the bit-shank. These jaws are secured in a vertical recess in the 80 drill-head by means of pivot-bolts which pass transversely through the head and through the jaws near their upper ends, the jaws being located one at either side of the upper portion of the vertical recess, so as to straddle 85 the arrow-headed portion B' of the bit-shank, whereby the upward pressure of the latter will tend to force the lower ends of the jaws apart and hold them normally in an expanded position. 90

To provide a smooth bearing-surface between the jaws and the inclined or beveled sides or edges of the arrow-head B' the jaws are formed at their lower ends with rounded portions on the inner sides thereof, and their lower-ends are concaved, as at *f'*, to provide cutting-edges *f*². At their upper ends on the inner sides thereof the jaws are beveled or inclined, as at *g*, to permit their lower ends to separate, and the adjacent faces of said 100 beveled portions are grooved, as at *g*²; for a purpose to be hereinafter described. The upper ends of the jaws are also cut away or recessed on the outer sides thereof, as at *g*², to

provide bearings or seats for the lower ends of the springs I, which latter preferably consist of stout steel plates which have elongated slots *i*, through which pass set-screws or bolts 5 *i*, by which the spring-plates are adjustably secured to the drill-head. These springs, being located above the pivotal center of the jaws E, exert a constant pressure, which tends to force the upper ends of said jaws together and consequently separate their lower ends, and at the same time serve as guards or shields which prevent mud and dirt from getting in behind the springs and into the joints, thus keeping the joints free from clogging 10 matter and in good working condition. Thus it will be seen that the jaws will be thrown outward by the pressure of the springs alone, and that when the drill is thrust downward the arrow-headed portion B' of the bit-shank 15 will also force said jaws apart and hold them firmly, so as to insure a successful operation, and any increased pressure or downward thrust upon the drill stock or rod for the purpose of forcing the bit or cutting-section A' 20 into the earth will result in correspondingly increasing the lateral pressure upon the depending cutting portions of the jaws E, and thereby force and hold them apart; but on the upward movement or when withdrawing 25 the drill the pressure of the pipe-section or casing upon the outer edges of the cutting-jaws will force the same inward, and as their lower ends bear upon the inclined sides of the pointed or arrow-headed end of the bit or 30 cutting-section A' the latter will be forced downward against the pressure of the spring or springs D, so as to permit the jaws to contract and allow the drill to be withdrawn. The upper ends of the jaws E are also ar- 35 ranged as shown in Fig. 1, so as to bear upon the upper wall of the vertical recess, and thus relieve the pivot-bolts which secure said jaws to the drill-head from undue strain. I also provide the drill-head with a longitudinal 40 bore or channel F, which extends vertically through the upper part of the drill-head and out through the boring-bar G, whereby water may be supplied to the cutting-surfaces, and by means of which the device may be kept 45 free from mud and dirt.

When it is desired to use the device as a pipe puller or lifter, the bolts which secure the springs I in place are loosened and the jaws E are removed. The dogs H (shown in 50 Fig. 4) may then be substituted for the jaws E by securing them in position by means of the same bolts that secure said jaws in place. The springs I are then adjusted so that their lower ends will be seated in recesses *h*, formed 55 in the necks of the dogs II, as shown, so as to hold said dogs in position for insertion in the pipe or casing, and at the same time retain the dogs in proper position for pulling or lifting the pipes.

60 From the foregoing description the operation of my invention will be readily under-

stood. When it is desired to lower the drill and reamer for operation beneath the lowermost section or casing of a previously-bored or partly-bored well, the jaws E are forced 70 inward against the pressure of the springs I and the bit A' is forced downward against the pressure of the spring D until the jaws occupy the position indicated in Fig. 2. In this position the device may be lowered with- 75 in the casing until it passes below the end of the lowermost section, whereupon the jaws will be thrown outward by the springs I and the bit will be thrown upward by the recoil of the spring D, in which position of the 80 parts drilling and reaming operations may be performed in the usual manner. By the de- scribed construction the downward thrust of the drill will cause an upward thrust of the bit, and thereby the arrow-headed shank of 85 the bit will be caused to force the cutting- ends of the reaming-jaws apart, and any in- crease of pressure upon the bit will corre- spondingly increase the pressure upon the arms E, and thereby insure the proper action 90 of the reaming-jaws.

When the device is adjusted for use as a pipe-puller, with the parts in the position in- dicated in Figs. 4 and 5, it may be lowered within the pipe or casing until the dogs catch 95 beneath the end of the section to be raised, (the sections being generally slightly sepa- rated at their joints, so as to permit this to be done,) and thereupon the section may be raised and removed from the well; but if a 100 section of pipe or casing cannot be raised for any reason, or if it is desired to remove the device without lifting the pipe-section it may be lowered until the dogs pass beneath the lowermost pipe-section, as indicated in Fig. 105 4, and thereupon the springs I will force the dogs apart sufficiently to cause the same to catch under the pipe, as shown in said figure, and by continuing the upward pull upon the device the springs I will be forced to release 110 the dogs and allow them to drop over, so as to permit the device to be removed from the casing.

It will of course be understood that the con- 115 struction and arrangement of the parts may be modified in a number of ways without de- parting from the spirit of my invention, and hence I do not desire to be limited to the ex- act construction and arrangement described and shown; but

120 What I claim, and desire to secure by Let- ters Patent, is—

1. In a combined drill and reaming-tool, the combination, with the drill-head provided with a vertically-elongated recess and a socket 125 at the lower end thereof, of the vertically- sliding bit or cutting-section fitted in said socket, the cutting-jaws or reamers pivoted near their upper ends in said recess and hav- 130 ing their lower cutting ends arranged to strad- dle the shank of said cutting-section, and the springs adjustably secured to the drill-head

and having their depending ends arranged to bear upon the short arms or ends of the cutting-jaws, substantially as described.

2. In combination with the drill-head having the recess and socket at the lower end thereof, the vertically-sliding bit or cutting-section fitted in said socket and provided with an arrow-headed shank, the cutting-jaws or reamers pivoted in said recess with their depending cutting ends arranged to straddle the shank of said bit, and the springs bearing on said jaws so as to force the cutting ends thereof apart, whereby said jaws are adapted to be normally expanded by the action of the springs and positively expanded by the action of the cutting-section on the downward thrust of the drill, substantially as described.

3. In combination with the drill-head, the vertically-sliding bit or cutting-section having an arrow-headed shank, the pivoted cutting-jaws arranged above said sliding bit, one at either side of the pointed arrow-headed shank, the springs adapted to hold said jaws in a normally-expanded position, and the spring for forcing said arrow-head upward between the depending cutting portions of said jaws, substantially as described.

4. In a combined drill and reaming-tool, the combination, with the recessed head, of the pivoted expandible cutting-jaws, and the vertically-sliding spring-pressed bit or cutting-section having the pointed head adapted to separate the cutting ends of said jaws, whereby the jaws will be normally expanded by the force of the spring and forcibly expanded by the upward pressure of the bit on the downward thrust of the drill and may be contracted against the pressure of the spring upon the bit on the withdrawal or upward movement of the drill, substantially as described.

5. In a combined drill and reamer, the combination, with the recessed drill-head having the socket at the lower end thereof, of the pivoted cutting-jaws, the vertically-sliding bit or cutting-section fitted to slide in said socket and having the enlarged head and

arrow-headed shank for limiting the movements of the bit, and the spring adapted to hold said bit normally in an elevated position, so as to expand the cutting-jaws, substantially as described.

6. In a combined drill and reaming-tool, the combination, with the drill-stock or boring-bar and recessed head having a water-channel leading to said recess, of the bit or cutting-section and the pivoted jaws having grooved upper ends communicating with the water-channel extending through the drill-head and boring-bar, substantially as described.

7. A convertible drill, reamer, and pipe-puller comprising the vertically-recessed drill-head, the spring-plates adjustably secured to said drill-head, with their lower ends depending below the upper wall of said recess, and the interchangeable cutting-jaws and pipe-lifting dogs, substantially as described.

8. In combination with the drill-head, the spring-plates adjustably secured thereto, and the removable pivot-bolts adapted to receive either the cutting-jaws or pipe-lifting dogs, substantially as described.

9. In combination with the drill-head provided with the vertically-elongated recess and the socket at the lower end thereof, the expandible cutting-jaws or reamers pivoted in said recess, the spring-plates bearing upon said jaws, so as to expand the cutting ends thereof, the vertically-sliding bit or cutting-section fitted in said socket and provided with an arrow-headed vertically-slotted shank, and the spring seated in the slot of said shank and adapted to force the same upward between the cutting ends of said jaws for the purpose of expanding the same, substantially as described.

In testimony whereof I affix my signature in presence of two witnesses.

HERMAN WEGNER.
